(57) **CLAIM**

The ornamental design for a trim systems component for building structures, as shown and described.

DESCRIPTION

FIG. 1 is a perspective view of the trim systems component for building structures of the present design;

FIG. 2 is a front end view thereof;

FIG. 3 is a rear end view thereof;

FIG. 4 is a right side view thereof;

FIG. 5 is a left side view thereof;

FIG. 6 is a top plan view thereof; and,

FIG. 7 is a bottom view thereof.
